UNITED STATES PATENT OFFICE.

WILLIAM H. GOSS, OF FRANKLIN TOWNSHIP, SOMERSET COUNTY, NEW JERSEY.

GAS-GENERATING BURNER.

Application filed February 8, 1926. Serial No. 36,888.

This invention relates to gas-generating burners, and the objects of the improvements are, first, to provide for the simple and economical casting of the device in a single piece, thereby eliminating a multiplicity of separate parts and providing a stronger, better, and more lasting structure; second, to provide for the prompt and thorough generation of gas by the efficient application of heat on the generator; and third, to prevent flooding of the device and the consequent waste of oil by the automatic control of the oil feed.

I attain these objects by the structure illustrated in the accompanying drawings wherein:

Figure 1 is a plan view of the device; Figure 2, a vertical longitudinal section of the same; Figure 3, a cross section on line 3—3 of Figure 1; Figure 4, a cross section on line 4—4 of Figure 1; Figure 5, an enlarged detailed view of the needle valve; and Figure 6, a detailed view in top plan of one end of the gas-generating cylinder, depicting a part of the float valve mechanism.

Describing the invention in detail, 1 designates the base of the device, which is relatively long and narrow, and provided with a flat bottom in order to rest firmly and easily upon the grate of the stove or furnace in which the device is placed. To further increase the stability of the device, supporting lugs 2 are provided at each corner of the base and project upwardly on opposite sides of the latter. Above the base and in line therewith is a hollow, barrel-shaped cylinder 3 in which gas is generated as hereinafter explained. This gas-generating cylinder is supported at its ends upon short vertical extensions 4—4' rising from the extremities of the base, as illustrated.

An auxiliary burner 5 extends along one side of the cylinder 3, and substantially in line with the bottom thereof, being joined thereto by the inturned portions 6—6' which are slightly inclined with respect to the horizontal, as seen in Figures 3 and 4. The base, cylinder, and side burner are preferably cast in one piece and the construction is so designed as to permit this to be easily accomplished, it being found in practice that a casting is more desirable than piping owing to its greater heat-resisting properties and the fact that it will not, therefore, burn out so quickly when sub-

jected to the intense flame and heat from the burner jets.

Fuel oil from a supply source is conducted by suitable piping to the inlet passage 7 leading inwardly of the vertical base extension 4 and communicating with the central passage 8 of the latter. Passage 8 opens outwardly through the base 1 and has its upper terminal communicating with a large opening 9 provided in one end of the cylinder 3. A similar opening 10 is provided in the opposite end of the cylinder, and threaded plugs 11 and 12 are inserted in the outer ends of the openings to close the same. Opening 9 constitutes the oil inlet to cylinder 3 and has a short bottom groove 13 from which the oil from passage 8 is permitted to flow and drip into the cylinder in small quantities at a time. Opening 10 constitutes the gas-outlet of the cylinder and is in communication with the vertical central passage 14 of the base extension 4', which passage likewise has its bottom opening in the base 1. Extending clear through the base and intersecting passages 8 and 14 is a central longitudinal bore 15 interrupted at one or more points by vertically disposed burner jets 16 having needle valve control 17. The bottom openings of passages 8 and 14 are closed by plugs 18 and 19, and the terminal ends of the base passage 15 are closed by plugs 20 and 21. All of these plugs are removable to permit access to the passages for purpose of cleaning, etc., and in order to prevent the oil from the inlet passage 8 from backing into the base passage, an internal plug 22 is adapted to be screwed or otherwise engaged in the vertical passage 8 just below the inlet 7.

The side burner 5 is cast solid in part, as shown at 23, and has the remaining part cored to provide a by-pass from the gas-passage 14 of the base extension 4', which by-pass consists of the intersecting passages 24 and 25. The outer ends of these intersecting passages are closed by removable plugs 26 and 27. Passage 25 is provided with one or more burner jets 28 having needle valve control 29 and disposed in an inclined plane so as to direct the flame against the bottom and to the opposite side of the gas cylinder. This arrangement is of particular advantage in connection with stoves or furnaces having the fire-box enclosed by a water-jacket, and in placing the improved device in such a stove or furnace,

it will be placed with the burner-less side of the gas cylinder disposed against one side of the water-jacket so that the flame from the side burner, after passing beneath the cylinder, will impinge the jacket walls and be thus applied direct to the jacket. Any number of gas burners may, of course, be used, according to the size of the furnace and capacity of the individual burner.

10 In order that the oil may be quickly and thoroughly converted into gas, only a small quantity at a time is admitted into the gas cylinder, and the feed is regulated in part by a float-controlled valve and in part by 15 the pressure of the generated gas. The valve mechanism consists of a long needle valve 30 extending downwardly for an appreciable distance into the inlet passage 8, and having at its lower end the usual needle 20 point 31 adapted to engage the valve-opening 32 in the valve seat 33. The valve seat is threadedly engaged in the passage 8 just above the inlet 7 and is removable through the bottom opening of the passage when the 25 plugs 18 and 22 are taken out. Valve 30 has a bracket 35 swiveled to its upper end and presenting spaced upstanding arms "a" and "b" connected by a pin "c" adapted to engage in a slot "d" formed in one end of 30 rod 34, from which the valve is suspended. By means of this arrangement, the valve has a free swinging movement for self-seating purposes as it is lowered onto its seat. Rod 34 extends inwardly of the cylinder 35 for nearly the entire length of the same and is pivoted at 36 to a plug 37 removably fitted in opening 9 of the cylinder. A float 38 is suspended from the free end of the rod and normally rests on or very close to the 40 bottom of the cylinder. A plug 39 engaged in opening 10 of the gas cylinder and extending inwardly thereof, has its inner portion bifurcated vertically to provide spaced guide fingers 40-40' adapted to extend on 45 opposite sides of the free end of the float rod. Top and bottom grooves 41 are formed in the body of the plug and communicate with the vertical passage 42 of the plug, which passage is in line with the gas 50 passage 14 of the device.

In the operation of the device, the float is adapted to be lifted by the inflow of only a small amount of oil, and the needle valve is adjusted and arranged to close when the 55 float is slightly elevated, the arrangement being such that at no time will the cylinder contain any great amount of oil. The base 1 of the device has its surface grooved to provide a priming pan or trough 43 and in 60 starting the device this pan is filled with gasoline or other priming material which is ignited to preheat the cylinder. As the cylinder becomes heated and the oil therein gasified, the gas vapors escape through outlets 41 and 42 into the gas passage 14 from

whence they are conducted to burners 16 and 28. When the level of the oil lowers in the cylinder, due to the vaporization thereof, the float drops and opens the needle valve 30. The pressure within the cylinder would normally prevent any oil from feeding into the cylinder, but as this pressure is diminished constantly by the escape of gas at the burner outlets, the oil is permitted to drip from groove 13 and becomes vaporized as it falls in contact with the heated bottom of the cylinder, against which the flames from the burner jet are directed. In the event of the flames becoming extinguished, with the resultant cooling of the cylinder, and the loss of pressure therein, the flooding of the entire device is prevented by the action of the float, which, upon the entrance of a small quantity of oil in the cylinder, is elevated the slight degree necessary to close 55 the needle valve and shut off further flow of the oil.

Having thus described my invention, what I claim as new and desire to secure by Letters Patent, is:

1. A gas-generating device comprising a casting presenting a hollow cylindrical gas chamber and a substantially solid base extending in spaced parallel relation to each other and connected at their extremities by short transverse portions, one of said short transverse portions having an internal oil passage communicating with the interior of the gas chamber and adapted to be connected with an oil supply source, the other short transverse portion having an internal gas passage forming an outlet from the gas chamber and communicating with an internal gas passage in the said base, a burner provided in the said base in communication with the said gas passage thereof, a valve in the said oil passage of the short transverse portion, and a float in the said gas chamber having operative connection with the said valve.

2. In a gas-generating device, a gas chamber having an oil inlet and a gas outlet, a removable plug provided in the gas chamber above the said oil inlet and a removable plug inserted therein also above the gas outlet, the said plug above the said gas outlet presenting inwardly directed guide fingers, a rod pivoted at one end to the plug above the said oil inlet and extending inwardly of the gas chamber with its free end disposed between the said guide fingers, a float suspended from the said free end of the rod, and a needle valve disposed in said oil inlet and detachably connected to the pivoted end of the said rod.

3. A gas-generating burner comprising a base having short vertical extensions, a gas-generating chamber supported upon said extensions and having an oil inlet at one end and a gas outlet at the other end, one of

said extensions having an internal oil passage leading to the said oil inlet and adapted to be connected with an oil-supply source and the other extension having an internal 5 gas outlet passage leading from the said outlet of the chamber, a burner extending along one side of the said chamber substantially in line with the bottom thereof, and in outwardly spaced relation thereto, 10 said burner having one end thereof joined to the last mentioned vertical extension and

provided with an internal passage having communication with the said gas outlet passage of the latter, and a burner jet provided in the said internal passage of the 15 said burner and disposed in an inclined plane to direct the flame against the bottom of the said chamber and under the chamber to the opposite side of the latter.

In testimony whereof I affix my signature.

WILLIAM H. GOSS.
